UNITED STATES PATENT OFFICE.

HARRY C. HOLLOWAY, OF GLENCOE, AND RAY V. DAWNEY, OF CHICAGO, ILLINOIS.

DERRICK TRUCK.

Application filed February 17, 1920. Serial No. 359,367.

To all whom it may concern:

Be it known that we, HARRY C. HOLLOWAY, a citizen of the United States, residing at Glencoe, in the county of Cook and State of Illinois, and RAY V. DAWNEY, a citizen of the United States, residing at Chicago, in the county of Cook and State of Illinois, have invented certain new and useful Improvements in Derrick Trucks, of which the following is a specification.

Our invention relates to improvements in derrick trucks, that is, small cars which may be pushed from place to place by workmen and provided with a derrick for lifting, carrying and placing frogs, switches and similar equipment.

One object of the invention is to provide a car or truck of this character in which the derrick is mounted so as to turn about a vertical axis, a turn-table being provided for this purpose.

Another object is to provide a truck of this character of generally improved construction.

25 In the accompanying drawings we have illustrated one embodiment of the invention.

Figure 1 is a front elevation of the truck.

Fig. 2 is a top plan view thereof with the derrick removed.

30 Fig. 3 is a side elevation of the body of the truck.

Fig. 4 is a section on the line 4—4 of Fig. 2, and

Fig. 5 is a section on the line 5—5 of Fig. 2.

The truck, which is preferably of standard gauge, is provided with two pairs of wheels 1, each pair being mounted on opposite ends of an axle 2, which is preferably rotatable, the axle being secured in brackets 3, which are secured to a frame or ring 4 in any suitable manner. This ring is preferably made from an angle iron. It supports a rotatable member composed of flat steel bars 5 carrying a plurality of rollers 6 between them, said rollers being mounted on bolts 7 passing through the bars 5 and being arranged to roll on the ring 4 as a track. The outside frame members are composed of angle irons 8, which rest on the bars 5, two additional angle irons 9 being arranged near the center of the frame between which are located two additional angle irons 10. All of these six angle irons

50 rest on the bars 5 and are secured in place by plates 11 riveted thereto. The bars 5

are arc-shaped, but do not form a complete circle, as shown in Figs. 2 and 3. There are preferably six of the rollers 6, four of said rollers being grouped near one side 60 of the frame and two near the other side. The four rollers are arranged on the side which supports the greatest weight. The angle irons 9 are bent upwardly, as shown in Fig. 1, and are then bent forwardly, extending out over the opposite side of the car to form the runway or track of the derrick. The angle irons 10 are also bent upwardly, the upper ends thereof being spread apart and carrying braces 12, which 65 brace the overhanging end of the derrick. The horizontal lower ends are shorter than the adjacent members 9, as shown in Fig. 2. The angle irons 8 are also bent upwardly and forwardly and are secured to the inclined part of the angle irons 9 to brace the same laterally. Additional angle irons 13 are provided, as shown in Fig. 1, to aid in supporting the overhanging portion of the derrick. 70

75 The derrick is provided with a suitable car 14, which travels on the inclined portion of the angle irons 9, said car supporting a chain 15, having a grapple 16 supported thereby. A windlass 17 is also provided, being operated by suitable gears 18, 19 and a handle 20, whereby frogs, switches and other parts may be raised by the grapple and moved about the yards or along the right of way. 80

85 To lock the turn-table against upward movement, a pair of rollers 21 is provided beneath two of the upper rollers 6, as shown in Fig. 4. The opposite side of the car is locked in place by a bar 22 sliding in suitable guides 23 and provided with a handle 24 at one end whereby the opposite offset end 25 may be made to project beneath the flange of the ring 4, thereby permitting the turn-table to be lifted without removing it 90 from the body of the car. When such removal is desired, however, it is necessary merely to operate the handle 24 thereby withdrawing the offset end 25, permitting the turn table to be moved toward the side of the car away from the lower rollers 21, thus withdrawing said rollers from beneath the ring 4 and permitting the turn table and the derrick supported thereon to be 100 lifted from the car body. 105

110 The ring is guided in its movement by a pair of rollers 26 (Fig. 2) turning about

a vertical axis and supported by the angle irons 8, thus maintaining the rollers 6 on the circular track. With the turn table arrangement provided, the derrick may be 5 swung through any angle thereby providing great flexibility in the movement thereof and facilitating the operation of lifting lengths of rails or other equipment.

The truck need not be of standard gauge, 10 but may be of narrow gauge or any special gauge. Various other changes may be made within the scope of the invention as expressed in the appended claim.

What we claim is:—
15. In a derrick truck, a circular angle iron

track having an inwardly extending horizontal flange, rollers resting on said flange, arc-shaped bars on opposite sides of said rollers and carried thereby, a plurality of angle irons arranged transversely on said bars, plates secured to said bars and to said angle irons, additional rollers carried by said bars beneath said flange, guides carried by said angle irons, a longitudinally movable locking rod supported by said guides, 20 and a handle for operating said locking rod.

In testimony whereof, we have subscribed our names.

HARRY C. HOLLOWAY.
RAY V. DAWNEY.
